UNITED STATES PATENT OFFICE.

FOSTER RUSSELL, OF SPOKANE, WASHINGTON.

WASHING-MACHINE DRAW-OFF.

1,399,800.

Specification of Letters Patent. Patented Dec. 13, 1921.

Application filed June 21, 1920. Serial No. 390,388.

To all whom it may concern:

Be it known that I, FOSTER RUSSELL, a citizen of the United States, residing at Spokane, in the county of Spokane and 5 State of Washington, have invented new and useful Improvements in Washing-Machine Draw-Offs, of which the following is a specification.

This invention relates to improvements in 10 washing machines and has to do particularly with that type of machine having a to and fro or oscillating tub mounted for movement inside of an outer housing or casing.

In this type of machine, the problem of 15 draw-off of the water from the tub is complicated by the fact that the water must be drawn off through the casing or housing thereby requiring an opening in the latter. With such opening, the tub must be in a 20 position of rest, in present constructions, in order to make connection or place the tub in discharging relation with the device mounted on the casing in order to discharge the water through the casing. With the crevices 25 and corrugations with which tubs are provided, they must be rocked manually, in order to get the water completely drained off.

Now the present invention has for its object 30 the provision of a novel form of draw-off for this particular type of machine in which the tub is always free to oscillate, or be manually oscillated, and wherein a draw-off connection is permanently established so 35 that water can be drawn off from the tub, through the casing, at any stage of operation, without requiring any opening in or of the casing, and with perfect freedom of movement of the tub to get all the water out 40 of the corrugations.

In carrying out my invention, in one form, a flexible connection is made between the tub and the outside of the casing in such a manner that while the tub is always free to perform 45 its oscillating movements, either by power or manually, it is permanently in draw-off connection so that the water may either be drawn off into a receptacle adjacent the outside of the casing, or to a point 50 remote from the machine.

My invention will be more clearly understood from the following description of the drawing and will be more particularly pointed out in and by the appended claims.

55 In the drawings:—

Figure 1, is a vertical sectional view of the

lower portion of a "Blue Bird" washing machine showing a part of the tub broken away and illustrating one manner of adapting the device of my invention thereto. 60

Fig. 2, is a plan view, partly in section, and more clearly showing the points of connection of the flexible draw-off.

Like characters of reference designate 65 similar views throughout the different figures of the drawing.

As shown, the machine is provided with a skeleton frame composed of verticals and laterals suitably mounted on casters 3. A casing or housing is vertically disposed about 70 the frame and the sides thereof are designated at 4, 5, 6 and 7, for convenience in the description to follow. A tub is shown at 8 and the same is mounted on the frame to oscillate about an axis indicated at 9. The 75 bottom wall of the tub, indicated at 10, is centrally elevated and openly corrugated for a purpose which is not pertinent to this invention but which is shown to illustrate the manner in which this invention operates to 80 drain a tub of established form. Lateral portions 11, of the tub, are the lowermost depending portions and a drain pipe 12 transversely spans the arch formed by the 85 elevated bottom 10 and has its ends in communication with the portions 11 near one extreme end of the tub adjacent wall 4, as shown in Fig. 2. This pipe 12, is at all times in open communication with the tub 8. All 90 of the foregoing is well known construction.

Next describing what constitutes my invention, 13 designates a nipple near the central portion of pipe 12 and extending horizontally therefrom toward wall 6. From Fig. 1, it will be seen that nipple 13, is 95 below the oscillating axis 9, and by reference to the dotted line position of the tub shown in Fig. 1, it will be seen that oscillating movement of the tub imparts a very considerable movement to nipple 13. Attached to this nipple 13, by any suitable clamp 14, is one end 15, of a flexible draw-off connection which may take the form of a rubber hose 16. Thus this hose 16 is in permanent draw-off connection with the 100 tub 8. This hose 16 is of sufficient length to extend from nipple 13 to wall 6. Means such as a supporting hook 17, attached to wall 6, may be employed to support the intermediate portion of the hose, although such 105 support is not essential to my invention. The remaining end 18, of the hose 16, is 110

shown fitted to the inner end of a cock 19, by means of any suitable clamp 20. The cock 19 is mounted in wall 5, at a point remote from wall 4, and very near to wall 6. Further, the hose 16, is of greatly excess length compared to a straight line intersecting the ends 15 and 18 thereof, there being a very considerable slack at the right of the support 17.

10 Now it will be clear that this excess length of hose permits of the utmost freedom of oscillating movement of the tub 8 without the slightest resistance, and further, the arrangement is such that the hose itself 15 will not be subjected to any such bending stresses as would be wearing. This results from the length of hose employed giving the same a long sweeping, instead of a sharp bending movement, following the action of 20 the oscillating tub.

It will be seen that the cock 19, outside of the casing, controls the draw-off, therefore, I not only entirely eliminate the usual door opening in the casing, which is 25 objectionable in many ways aside from the initial cost, but I provide the tub with a draw-off which is at all times available irrespective of the position of the tub, or whether it is at rest or in motion. It will 30 be obvious that if it is desired, the hose may be connected directly with the sewer or other place of deposition.

It is believed that my invention will be clearly understood from the foregoing, and 35 I do not wish to be limited except for such limitations as the claims may import.

I claim:

1. A washing machine comprising an outer closed casing and a tub mounted for to and 40 fro movement in said casing, characterized by a flexible draw-off tube structure in fixed water receiving connection with said tub and extending through said casing and having a cock outside of said casing, whereby 45 draw-off from said tub may be effected from the exterior of said casing without requiring an opening therein.

2. A washing machine comprising an outer closed housing and a tub mounted for

to and fro movement inside of said casing, 50 characterized by a flexible draw-off tube having one of its ends connected to said tub and having its remaining end connected to a portion of the said casing, a draw-off cock connected with the casing end of said tube and accessible from the exterior of said casing, said tube being of sufficient length to enable the tub to freely oscillate irrespective of the draw-off through said tube.

3. A washing machine comprising an outer closed casing and a tub mounted for oscillating movement inside of said casing, characterized by a flexible draw-off tube having one of its ends connected to one end portion of the tub, the remaining end of said tube being in fixed connection with the casing said tube being of sufficient length to provide freedom of movement of said tub without resistance from said tube, the casing connection of said tube including a 70 cock accessible for draw-off from the exterior of said casing irrespective of whether the tub is at rest, in a tilted position or in motion.

4. A washing machine comprising an outer closed casing and a tub mounted for oscillating movement inside of said casing, characterized by a flexible draw-off tube having one of its ends connected substantially 75 centrally near one extreme end portion of 80 the tub and off-center with respect to the axis of oscillation of said tub, the remaining end of said tube extending across the interior of the casing and being in fixed connection with a side of the casing, and 85 said tube being of sufficient length with respect to a straight line intersecting the points of connection of the ends of said tube with said tub and casing to afford freedom of movement of said tub without resistance from said tube, and means for controlling egress of water from the casing end of said tube, and means for supporting an intermediate portion of said tube.

In testimony that I claim the foregoing 95 as my own, I hereby affix my signature.

FOSTER RUSSELL.
